Inventor:

Reuben G. Holmes

UNITED STATES PATENT OFFICE.

REUBEN G. HOLMES, OF WORCESTER, MASSACHUSETTS.

IMPROVED CLOTHES-WRINGER.

Specification forming part of Letters Patent No. **39,813**, dated September 8, 1863; antedated January 21, 1863.

To all whom it may concern:

Be it known that I, REUBEN G. HOLMES, of the city of Worcester, county of Worcester, and State of Massachusetts, have invented a new, useful, and Improved Machine for Wringing Clothes; and I hereby declare that the following is a full, clear, and exact description of the construction of the same, reference being had to the annexed drawing, making a part of this specification.

To enable those skilled in the art to fully understand and construct my invention, I will proceed to describe it.

The letters A A on the drawing represent the two posts of the machine.

The letter B represents the lower or stationary roller.

The letter C represents the upper or adjustable roller.

The letters D D represent a groove in which the boxes, as shown by E E, and the followers, as shown by F F, vibrate.

The letters E E represent metallic boxes for bearings at each end of the roller C.

The letters F F represent followers on the boxes E E at each end of the machine.

The letter G represents a cross-bar placed on top of the two posts A A, to which it is firmly secured at each end.

The letters H H represent two india-rubber springs, placed over the lower spring, I, and under the bar G at each end of the machine.

The letters I I represent two springs, the upper spring resting upon the followers F F. The lower spring bears up against the india-rubber springs H H, and both springs are secured and adjusted by a stationary screw in the center of the bar G, the screw represented by the letter J, thus forming a combination of the two springs, thereby obtaining a more equal, self-adjusting, and greater power.

The letter J represents a stationary screw, passing through the center of the bar G, connecting and regulating the two springs, as shown by I I.

The letter K represents the shaft passing through the lower roller, B.

The letter L represents the crank, which is attached to one end of the shaft K in a firm manner.

I do not claim any of the above-described parts, irrespective of their particular application and arrangement herein shown; but

What I do claim as my invention, and for which I desire to secure Letters Patent, is—

The combination of the two springs, as shown by I I, as fully set forth in this specification.

REUBEN G. HOLMES.
